(57) **CLAIM**

The ornamental design for a pet nail clipper, as shown and described.

DESCRIPTION

1. Pet nail clipper.

Fig. 1.1 is a front elevation view of a pet nail clipper showing my new design;

Fig. 1.2 is a top plan view thereof;

Fig. 1.3 is a right side elevation view thereof;

Fig. 1.4 is a left side elevation view thereof;

Fig. 1.5 is a back view elevation thereof;

Fig. 1.6 is a bottom plan view thereof;

Fig. 1.7 is a front, left perspective view thereof; and

Fig. 1.8 is a front elevation view showing the pet nail clipper of FIG. 1 in a condition for use.

The present article is a pet nail clipper wherein a recess is formed at the distal end of both blades; a nail placed in the recess is nipped by the blades, whereby the nail is cut.

In all of the drawings, the equal-length broken lines depict portions of the pet nail clipper that form no part of the claimed design. The equal-length broken line surrounding the paw print indicia on the pet nail clipper forms no part of the claimed design. The dash-dot-dash lines define boundaries of the claim.
